SHAPER MECHANISM FOR WINDING YARN ON WEFT BOBBINS IN SPINNING MULES

Application filed August 19, 1929, Serial No. 386,883, and in Great Britain December 7, 1928.

The invention relates to bunch building mechanism of self-acting mules for spinning and winding yarn on weft bobbins for subsequent use in plain power looms, of the kind whereby the shape or length of the chase may be varied or adjusted with the assistance of a supplementary coppering rail and means for raising and lowering the same for this purpose.

10 Hitherto, in the spinning and winding of bobbins for automatic weft-replenishing looms, bunch building mechanisms have been used comprising a supplementary shaper shoe instead of the above-mentioned supplementary coppering rail, with means for raising and lowering the shoe relative to the normal coppering rail. Provision is also made therein whereby exactly the same amount of yarn will be contained in the bunch on each bobbin; also, 15 for varying the said amount, and for rendering the means adapted to build the said bunch inoperative and the mule to operate in the usual manner. The use of a supplementary coppering rail has also been used in connection 20 with bunching motions on self-acting spinning mules.

The object of the present invention is an improved bunching motion applicable to self-acting mules, comprising an improved construction of the supplementary or auxiliary coppering rail; the means for forming the bunch of a predetermined amount of yarn; the means for manually resetting and supporting the supplementary coppering rail to 25 build a bunch of yarn at the base of the bobbin; and the means for immediately lowering the supplementary rail on completion of the desired bunch, whereby a demarkation is made between the said bunch and the normal 30 winding of the yarn on the bobbin, in order that when the bobbin approaches a certain stage of exhaustion in a plain power loom the said bunch and the demarkation are exposed to view, indicating to the weaver the number 35 of drafts of yarn or picks of weft still remaining on the bobbin. Should the short traverse, chase or bunch of yarn represent, for example, three picks of weft, the loom may be stopped 40 for weft replenishing immediately following the next two picks, which leaves one pick or

draft of weft or yarn on the bobbin to become waste.

Under existing conditions the weaver may have to stop the loom several times in ascertaining or obtaining the desired stage of 55 exhaustion of the weft, and frequently when the shuttle is changed, anything from three or more picks of weft may still remain on the bobbin, all of which amount to so much waste and is mainly due to the normal or much 60 longer traverse or chase and the want of any indication as to the state of exhaustion, found throughout the customary weft bobbins, in this type of loom.

According to the invention an additional 65 or auxiliary shaper rail is preferably provided placed in any suitable or desired position but preferably arranged parallel and in close proximity to the existing or main shaper rail, with one end pivoting thereon. The 70 auxiliary rail is adapted to be operated separately or independently of the main rail and on commencing to wind the yarn on to each set of bobbins, is set at an angle thereto; the pulley or runner on the corresponding 75 faller leg mechanism in engaging the said auxiliary rail when in its raised position, is raised out of engagement with the main rail, and the predetermined angle thereof produces at the commencement of winding 80 operations a relative short traverse, taper or chase in the yarn when it begins to be wound on to the bobbin or cop. The predetermined amount of yarn wound thereon while the auxiliary rail is in the raised position may 85 represent in length preferably three or four drafts or draws of yarn, or picks of weft, and immediately following the third or fourth draft or draw, according to which is preferred, the said rail is automatically and 90 quickly lowered to the level of or slightly below the main rail, the runner on the faller leg mechanism then engages the normal or main rail setting up the normal traverse or chase which continues during the rest of the 95 winding of the set of bobbins, producing demarkation between the long and the short chase.

Means are provided during the setting of the shaper shoes, for raising the auxiliary 100

shaper rail, or, where the auxiliary rail is dispensed with, the main shaper rail; for supporting said rails in the raised position; for lowering the rail to set up the normal 5 traverse or chase in the winding of the yarn; and for releasing certain mechanism controlling the short traverse or chase in readiness for winding the next set of bobbins.

The invention will now be described with 10 reference to the accompanying drawings, in which:—

Fig. 1 is a side elevation of a fragmentary part of a woollen spinning mule, showing the normal shaper rail with an additional or 15 auxiliary shaper rail pivoted thereon the latter being shown in broken lines in its normal and in its raised positions, and means for operating said auxiliary rail and for holding the same in the raised position.

Fig. 2 is a side elevation of the form of knocking-off mechanism preferably employed for controlling the auxiliary shaper rail, showing in broken lines the relative arrangement of the shaper shoes, connecting 20 rod, and main and auxiliary shaper rails of a woollen spinning mule.

Fig. 3 is a plan view of Figs. 1 and 2 assembled.

Fig. 4 is a transverse section through the 30 line 4—4 of Fig. 2 of a part of the knocking-off mechanism shown at Fig. 2.

Fig. 5 is a similar view through the line 5—5 of Fig. 2.

Fig. 6 is a view of a fragmentary part of 35 the knocking-off mechanism showing in full lines the position of the pivoted lever and catch at the termination of each traverse of the carriage, and means for preventing their return on the completion of a bunch or short 40 chase of yarn on the base of the bobbin or cop, and immediately prior to the lowering of the auxiliary rail for normal spinning.

Fig. 7 is an elevation of a fragmentary part 45 of a bobbin showing the short chase formed in the yarn at the commencement of winding operations and the subsequent or normal chase adhered to throughout the rest of the spinning and winding of the yarn thereon.

Referring to Fig. 1:—1 is the main shaper 50 or copping rail provided at each end with trunnions 2, adapted to engage inclined faces on the shaper shoes 3 and to be operated by the usual means in the well known manner. A preferably movable additional or auxiliary shaper rail 4 is arranged parallel to the rail 1, pivoting at one end upon a stud 5 secured thereto the opposite end being provided with a recess or the like 6 adapted to engage and to be normally supported by one of the trunnions 2 on the corresponding end of the rail 1. The auxiliary rail 4 is adapted to operate and to be operated separately or independently of the main rail, and for this purpose it has pivotally mounted thereon two 60 arms or levers 8, 9, which may be adjustable 65

as to their length adapted to move on the pivots 10, 11, respectively in one direction and to remain rigidly vertical by means of projections 12, 13, adapted to engage the underside of the rail 4 when an effort is made to move them in an opposite direction. The arms or levers 8, 9 are also adapted to be moved in relative opposite directions, the arm or leg 8 is of greater length than the arm 9 and normally occupies an inclined position. In some mules the gravity lever or leg 8 may be made to pivot or swing on a stud carried by a bracket secured to the main shaper rail and has one arm longer than the other, the shorter arm being also provided with an adjustable stud forming an extension thereof, but in place of the said leg 8 supporting the raised rail 4, resting on the base or floor as clearly shown at Fig. 1, the stud on the short arm of the leg is adapted to engage the underside of said rail to support the same, the weight thereof resting on the pivot stud of the leg, the fulcrum of the rail 1 being on the back shoe 3. To the rod 14 connecting the front and back shaper shoes 3 is secured a bracket 15 provided with an inclined plane 16 of a greater angle than the aforesaid inclined surfaces of the shaper shoes, adapted on the setting of the latter in the well known manner to engage the arm 9, 90 for the purpose of raising the rail 4.

Referring to Figs. 2 and 3:—In connection with the above-mentioned auxiliary shaper rail, is provided suitable knocking-off mechanism comprising a spring biased 100 movable rod or bar 17 suitably supported by guide brackets 18 and by a lever 19; the rod or bar has formed thereon a series of inclined planes or teeth 20 at one end and at the opposite end it is provided with a slot 21 adapted to be engaged by a stud 22 on the lever 19. The teeth 20 are adapted to be engaged by pawls 23, 24, the ratchet 23 pivots at 25 on a lever 26 pivoting at 27 on a bracket 28 integral with a base 29; the catch 24 pivots at 30 on an extension 31 of one of the brackets 18.

A spring 32 is connected at one end to a projection or bolt 33 on the rack 17 and at the opposite end it is secured to an adjustable screw 34 mounted on a fixed bracket 35; a further spring 36 around the boss 37 of lever 19 is secured at one end to the collar 39 of the stud 39^A, the other end being fastened to the said lever 19.

The lever 26 is normally positioned at a suitable angle and a projection or the like 40 thereon rests against an adjustable stop 41 carried by a bracket 42 on the base 29. An adjustable screw 43 mounted on the loose end of the said lever is adapted to be engaged at each draft of yarn or on the outward traverse of the mule carriage, by an arm or bracket 44 secured to the back of the square 45. A further adjustable stop 46

mounted in a bracket 47 secured to or integral with the rack bar, is adapted to engage the lever 26 following the final operation of said bar, or when the desired number of 5 drafts of yarn for forming the bunch or short taper of yarn has been wound on the bobbin or cop, to prevent it being again engaged by the bracket 44 on the next outward traverse of the carriage.

- 10 Upon the connecting rod or bar 14 and approximately spaced in accordance with the two pawls 23, 24, are secured brackets or fingers 48, 49, the bracket 48 being preferably of greater width than the bracket 49, 15 and both are provided with round or bevelled faces adapted at a predetermined time to engage pivoted levers or arms 50, 51, on the said pawls, to move the same into engagement with corresponding studs 53, 54, 20 for the purpose of raising the pawls out of engagement with the rack bar. Provision is also made on the said pawls by means of further studs and a recess thereon or therein, whereby the pawls on their release again 25 drop into engagement with the teeth of the said bar. 55 is the normal pulley or runner on the corresponding faller leg mechanism adapted to engage one or both rails 1, 4, on its traverse; it is when traversing the rail 4 30 after it has been raised and set at a relative different angle to that of the main rail 1, that the desired bunch or short chase in the yarn at the base of the bobbin or cop is produced, for the purposes before described.
- 35 Spaced perforations 57 are formed in the bar 17. Each perforation or hole counting from the right of the bracket 18 represents one draft of yarn and one operation of the pawl 23 moving said bar a distance of one 40 tooth, and is adapted to receive a detachable projecting pin or cotter 59; the amount of movement of the bar 17 according to the number of drafts of yarn to form the desired bunch or short chase aforesaid, may be regulated or adjusted by placing the pin 59 45 in the hole nearest the said bracket 18. When the rack bar 17 is moved forward by pawl 23 on lever 26 a distance of one tooth representing one draft of yarn, knock-off lever 19 will be drawn forward to operate lever 8 owing to stud 22 being at the end of slot 21. For each additional draft of yarn, or for example, for forming a bunch of three 50 drafts of yarn, the bar 17 may be set a corresponding distance back from said stud 22 (as shown at Fig. 3) and the pin again placed in the hole 57 nearest the bracket 18 so that when the bar 17 is released following the operation of lever 8 and is drawn back, 55 the aforesaid pin or cotter engages the bracket 18 which serves as a stop preventing its further withdrawal and ensures that the cycle of operations or the predetermined drafts of yarn wound on the bobbin or cop, 60 be repeated in the next set.

In the functioning of this invention the spinning and winding of the yarn upon a set of bobbins leaves the rack bar 17 at the end of its traverse where it is held following the lowering of the rail 4 for normal spinning 70 by the pawls 23, 24, lever 26, and stop 46 as clearly shown at Fig. 6 of the drawings, and with the fingers or brackets 48, 49 in the positions shown in Fig. 3. When it is desired

75 to spin and wind the yarn upon a further set of bobbins the next setting of the shaper shoes first causes the said fingers 48 and 49 to engage the levers 50 and 51 moving them into engagement with the pins 53, 54 on the pawls 23, 24, to lift the said pawls out of engagement with the teeth 20 and release the bar 17 which is returned to its normal position by the spring 32; the continued setting of the shaper shoes brings the face 16 of the bracket 15 on the connecting rod 14 into engagement 80 with the lever 9 on the rail 4, which is prevented from being moved on its pivot in this direction by the projection 13, raises the said rail at the same time the main rail 1 is being raised by the shoes 3, the angle of the face 16, however, being greater than the faces of the said shoes imparts an increased and quicker movement to the said rail 4 and at the same time lifts the lever or leg 8 from 85 its normal inclined position until it is adapted to swing on its pivot and assume by gravity a vertical position; when this occurs the lever 9 passes the peak of the incline 16 and in moving out of engagement therewith descends a second incline on the brackets 15, 90 lowering the leg 8 into engagement with the floor to support the rail 4 in the desired position above and at a different angle to the rail 1, as is clearly shown at Figs. 1 and 2 of the drawings. When this operation has taken place the setting aforesaid ceases, and the spinning of the yarn forming the bunch or 95 short chase commences.

100 In the formation of the aforesaid short chase 58 (see Fig. 7), the screw 43 on the lever 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960

operate the lever 19 for the latter to engage and move the leg 8 out of the perpendicular for the purpose of rendering the rail 4 inoperative by the following or the lowering 5 the same to the level of or slightly below the main shaper rail 1, to recommence normal spinning for the purpose before described. During the operation of the lever and its return by the springs 36, the stop 46 on the bar 10 17 has been also moved into the position shown clearly at Fig. 6, and during the normal or subsequent spinning and winding of the yarn on the bobbin or cop in the well known manner, prevents any further operation 15 of the lever 26 and pawl 23 by the carriage. On commencing a further set of bobbins, the bar 17 is again released and the auxiliary rail 4 raised into position by the resetting of the shaper mechanism in the 20 manner before described.

Following the lowering of the rail 4 and during the normal spinning and winding operations, the shaper shoes are returned lowering the shaper rails in the well known manner; no opposition is offered to the simultaneous return of the bracket 15 and the fingers 25 48, 49 on the rod 14, as the levers 9, 50 and 51 are free to move on their pivots in the same direction, and the leg 8 to flatten out. The 30 positioning of the said bracket and fingers on the said rod relative to the lever 9 and pawls 23, 24, is such as to ensure the carrying out of their functions at predetermined times for producing the desired effect; the 35 same applies to the positioning on the bar 17 of the stop or screw 46 relative to the first tooth in said bar and the lever 26, for the purposes before described. The greater width of the finger 48 is adapted to ensure 40 the return of the rack bar on its release before the pawl 23 is allowed to re-engage therewith.

What we claim as our invention, and desire to secure by Letters Patent, is:—

45 1. A shaper mechanism for spinning mules, comprising a main shaper rail, an auxiliary shaper rail movably connected to said main shaper rail, means for raising said auxiliary shaper rail above said main shaper 50 rail, means for maintaining the auxiliary shaper rail in its raised position, a rack bar, means on said rack bar for lowering the auxiliary shaper rail, means operatively associated with said rails and said rack bar adapted initially to wind on the bobbins or 55 cops a predetermined bunch of yarn of relatively short chase at the bottom thereof and thereafter a longer or normal chase whereby to provide a demarkation between the short 60 chase and the normal chase.

2. In combination with a spinning mule carriage, a shaper mechanism having shaper shoes, a rod connecting said shoes, a main shaper rail movable on said shoes, an auxiliary shaper rail movably connected to said 65

main rail, a rack bar, means on said rack bar operatively connected to the auxiliary shaper rail for lowering the same, yieldable means for maintaining said bar in one position and means operatively associated with the mule carriage for moving said rack bar whereby to provide a demarkation at predetermined points in the yarn. 70

3. In combination with a spinning mule carriage, a shaper mechanism having shaper 75 shoes, a rod connecting said shoes, a main shaper rail movable on said shoes, an auxiliary shaper rail movably connected to said main rail and arranged to be moved at an angle above the same, a rack bar, yieldable means for moving the rack bar in one direction, a lever having a pawl arranged to engage in the teeth of said rack bar, and means operatively associated with the mule carriage for moving the rack bar in the opposite direction a distance of one tooth for each draft 80 of yarn, whereby to provide a demarkation between the initial chase and the normal chase on the bobbin. 85

4. In combination with a spinning mule 90 carriage, a shaper mechanism having shaper shoes, a rod connecting said shoes, a main shaper rail movable on said shoes, an auxiliary shaper rail pivoted to said main rail and arranged to be moved to an angle different 95 from that of the main rail, a rack bar, a pair of spaced pawls arranged to engage said rack bar, means connected to one of said pawls for moving the same out of engagement with said rack bar and means on said connecting rod for moving both of said pawls out of engagement with said rack bar, whereby to provide a demarkation between the initial chase and the normal chase on the bobbin. 100

5. In combination with a spinning mule 105 carriage, a shaper mechanism having shaper shoes, a rod connecting said shoes, a main shaper rail movable on said shoes, an auxiliary shaper rail pivoted to said main rail and arranged to be moved to an angle different 110 from that of the main rail, a rack bar, a pair of spaced pawls arranged to engage said rack bar, means on said rod for raising said pawls out of engagement with said rack bar at predetermined intervals, means for raising said auxiliary shaper rail above the main shaper rail to produce a short chase in the arm at the base of the bobbin, means for lowering the auxiliary shaper rail to substantially 115 the same level as the main shaper rail and producing the normal chase of the arm, and means for maintaining said auxiliary shaper rail in its inoperative position. 120

6. A shaper mechanism for spinning mules comprising a main shaper rail, an auxiliary shaper rail movably connected to the main shaper rail, supporting means movably connected to said auxiliary rail for maintaining the same in a raised position, shaper shoes, a rod connecting said shoes, means on said 125 130

rod adapted on the resetting of said shoes to operatively engage the said supporting means to lift the auxiliary rail into its active position for the purpose of forming the initial or short chase, a mule carriage adapted to 5 traverse the raised auxiliary rail, means associated with said carriage adapted to be operated thereby in accordance with the number of drafts of yarn required to form a bunch, and means on completion of said bunch, adapted to simultaneously move the supporting means, so as to allow said auxiliary rail to drop to its inactive position, thus causing the mule carriage to next engage the main shaper rail for normal winding, thereby creating a distinct demarkation in the yarn between the said bunch and the normal or longer chase.

7. A shaper mechanism for spinning mules comprising a main shaper rail, an auxiliary shaper rail movably connected to the main shaper rail, spaced supporting means movably connected to said auxiliary rail, shaper shoes, a rod connecting said shoes, means on 20 said rods adapted on the resetting of said shoes to operatively engage one of said supporting means to lift the auxiliary rail into its active position for the purpose of forming the initial or short chase necessary to bunch 25 the yarn on the bobbin and allowing the other supporting means to be moved into a position temporarily supporting said auxiliary rail in the said position, a mule carriage adapted to traverse the raised auxiliary rail, means associated with said carriage adapted 30 to be operated thereby in accordance with the number of drafts of yarn required to form a bunch, and means on completion of said bunch adapted to simultaneously move 35 said supporting means to allow the auxiliary rail to drop to its inactive position, causing the mule carriage to next engage the main shaper rail for normal winding.

8. A shaper mechanism for spinning mules comprising a main shaper rail, an auxiliary shaper rail movably connected to the main shaper rail, spaced supporting means movably connected to said auxiliary rail, shaper shoes, a rod connecting said shoes, means on 40 said rod adapted on the resetting of said shoes to operatively engage one of said arms to lift the auxiliary rail into its active position for the purpose of forming the initial or short chase necessary to bunch the yarn on the bobbin and allowing the other arm to move to a position temporarily supporting said auxiliary rail in the said position, a mule carriage adapted to traverse the raised auxiliary rail, means associated with said carriage adapted 45 to be operated thereby in accordance with the number of drafts of yarn required to form a bunch, and means on completion of said bunch adapted to simultaneously move said supporting arms to allow the auxiliary rail to drop to its inactive position, causing the mule

carriage to next engage the main shaper rail for normal winding, thereby creating a distinct demarkation in the yarn between the said bunch and the normal or longer chase.

9. A shaper mechanism for spinning mules, comprising a main shaper rail, and an auxiliary shaper rail movably connected to said main shaper rail; supporting arms movably connected to said auxiliary rail; shaper shoes, a rod connecting said shoes, means secured to said rod adapted on the resetting of said shoes, to operatively engage one of the said arms to lift the auxiliary rail into the active position for the purpose of forming the initial or short chase necessary to bunch yarn on a bobbin and allowing the other arm on said auxiliary rail to gravitate into a position to temporarily support the auxiliary rail in the said position; a mule carriage adapted to traverse the raised auxiliary rail; a movable rack associated with means intermittently operated by the mule carriage in accordance with the number of drafts of yarn required to form the bunch; means integral with said rack and in operative engagement with a resilient lever adapted on the completion of a bunch, to simultaneously move one of said arms and drop the auxiliary rail into the inactive position so as to cause said mule carriage to next engage the main shaper rail, thus creating a distinct demarkation in the yarn between the initial chase and the normal or longer chase.

10. A shaper mechanism for spinning mules, comprising a main shaper rail, and an auxiliary shaper rail movably connected to said main shaper rail; arms movably connected to said auxiliary rail; shaper shoes, a rod connecting said shoes, means secured to said rod adapted on the resetting of said shoes to operatively engage one of the said arms to lift the auxiliary rail into the active position for forming the initial or short chase necessary to bunch yarn on a bobbin, and allowing the other of the arms on the auxiliary rail to gravitate into a position to temporarily support the rail in the said position; a mule carriage adapted to traverse the said auxiliary rail; a movable rack, a spring yieldably maintaining the rack in one position, a slotted extension thereof, a resilient lever in engagement with said extension, a lever and pawl mechanism operatively associated with the mule carriage when traversing the auxiliary rail to intermittently move said rack in opposition to said spring in accordance with the number of drafts of yarn required to form a bunch, and on completion of said bunch to operate said resilient lever to move the gravity arm and drop the auxiliary rail to its inactive position, causing said mule carriage to next engage the main shaper rail for normal winding, creating a distinct demarkation between the initial chase and the normal or longer chase.

11. A shaper mechanism for spinning

mules comprising a main shaper rail and an auxiliary shaper rail movably connected to said main shaper rail; spaced supporting arms movably connected to said auxiliary rail, shaper shoes, a rod connecting said shoes, means secured to rod adapted on the resetting of said shoes to operatively engage one of the said arms to lift the auxiliary shaper rail into the active position for the purpose of forming the initial or short chase necessary to bunch yarn on a bobbin, and allowing the other of said arms to gravitate into a position to temporarily support the rail in the said position; a mule carriage adapted to traverse the said auxiliary rail; a movable rack having a slotted extension, a spring yieldably maintaining the rods in one position, a resilient lever in engagement with said extension, a lever and pawl mechanism operatively associated with the mule carriage when traversing the auxiliary rail to intermittently move said rack in opposition to said spring in accordance with the number of drafts of yarn required to form a bunch, and means movable with the rack adapted on the dropping of the auxiliary rail to engage the lever and pawl mechanism and hold them out of engagement with the mule carriage during normal winding, or until the next resetting of the shaper shoes.

12. A shaper mechanism for spinning mules, comprising a main shaper rail, an auxiliary shaper rail movably connected to said main shaper rail, spaced supporting arms movably connected to said auxiliary rail, shaper shoes, a rod connecting said shoes, means secured to said rod adapted on the resetting of said shoes to operatively engage one of the said arms to lift the auxiliary shaper rail into the active position for the purpose of forming the initial or short chase necessary to bunch yarn on a bobbin, and allowing the other said arms to gravitate into a position to temporarily support said rail in the said position; a mule carriage adapted to traverse the raised auxiliary rail; a movable rack; a lever catch and pawl mechanism intermittently engaged by said mule carriage to move said rack in accordance with the number of drafts of yarn required to form a bunch; means secured to said rod connecting adapted to engage means on the pawl mechanism on the resetting of said shoes to disengage the pawls and release the rack; and adjustable means on said rack adapted on the release thereof to engage a fixed part of the device to ensure the cycle of operations being repeated on the next resetting of the shaper shoes.

60 In witness whereof we affix our signatures.
